FIG. 4.

FIG. 2.

INVENTOR
ALBERT ANGERMAYER
Hazard and Miller
ATT'YS.

UNITED STATES PATENT OFFICE.

ALBERT ANGERMAYER, OF LOS ANGELES, CALIFORNIA.

TOBACCO-PIPE.

1,289,071.

Specification of Letters Patent. Patented Dec. 31, 1918.

Application filed July 15, 1918. Serial No. 245,033.

To all whom it may concern:

Be it known that I, ALBERT ANGERMAYER, a citizen of Germany, residing at Los Angeles, in the county of Los Angeles and State of California, have invented new and useful Improvements in Tobacco-Pipes, of which the following is a specification.

My object is to make an improved tobacco pipe and my invention consists in the novel features herein shown, described and claimed.

Figure 1 is a perspective of a tobacco pipe embodying the principles of my invention.

Fig. 2 is a vertical central section on an enlarged scale.

Fig. 3 is a top plan view, the stem being broken away.

Fig. 4 is a horizontal section on the line 4—4 of Fig. 2.

The bowl 1 is preferably made of wood and has a flat upper end face 2, a downwardly tapered chamber 3 extending from the flat end face 2 to the bottom 4 and a bore 5 extending from the bottom 4 to the lower flat face 6.

The stem section 7 is formed integral with the bowl 1 at one side and is substantially half way between the upper face 2 and the lower face 6, and the opening 8 through the stem section communicates with the chamber 3.

The mouthpiece 9 is connected to the stem section 7, and the passage 10 through the mouth piece connects with the passage 8.

A cork bushing has a portion 11 fitting in the upper end of the chamber 3 and a portion 12 fitting the upper face 2, there being a central opening 13 through the bushing. 13 is a heat insulator ring of mica or the like to protect the bushing 13.

The tobacco container 14 is formed of flat sheet metal such as aluminum about a hundredth of an inch thick cut into the desired shape and then rolled into a cylinder. The container thus formed has a portion 15 fitting in the bore 5, a portion 16 extending upwardly from the portion 15 in the chamber 3, said portion 16 being upwardly flaring or downwardly tapered so that its upper end is slightly larger than its lower end, and the portion 17 extending upwardly from the upper end of the portion 16 and fitting in the opening 13 in the cork bushing portion 11. Horizontal rows of perforations 18 and 19 are formed through the portion 16 of the container below the bushing 11 and a row of

perforations 20 is formed through the portion 17 above the bushing. A metal cap 21,

preferably stamped from sheet aluminum about a fiftieth of an inch thick, fits against the upper face of the cork bushing around the portion 17 of the container and downwardly around the periphery of the portion 12 and covers the joint between the portion 12 and face 2, and spring fingers 22 extend downwardly from the cap and snap into recesses formed in the periphery of the bowl 1 to hold the cap removably in place.

It is intended that the cap 21, the cork bushing, and the container 14 may be readily removed from the bowl 1 and that the spring fingers 22 will hold the parts all tight when the pipe is in use.

A sieve 23 is inserted downwardly through the portion 17 to a point substantially halfway between the perforations 20 and the perforations 18 and driven tightly into place.

The container 14 at the sieve 23 is about four-fifths of an inch in diameter and the chamber 3 is about one and three-quarters inches deep. The inside diameter of the portion 15 of the container is about two-thirds of an inch. The sieve 23 is stamped from sheet metal, preferably a good aluminum and copper alloy that will not corrode or oxidize under the heat generated by the burning tobacco.

A handle 24, formed of brier wood, has a knurled annular periphery 25, a flat lower face 26, a flat upper face 27 fitting the face 6, and a circular recess 28 within the face 27. A cork plug 29 is seated in the recess 28 and adapted to fit within the portion 15 of the container.

An expansive coil spring 30 fits loosely in the portion 16 of the container and has a straight end 31 anchored in the part 29, and a follower 32 is attached to the upper end of the spring 30, said follower being a perforated disk stamped from aluminum about a fiftieth of an inch thick and six-tenths of an inch in diameter so as to fit loosely in the chamber 33 in the tapered portion 16 of the container.

In the practical operation, the bowl 1 is turned bottom upward, the cork 29 removed, and the tobacco is inserted downwardly through the portion 15 of the container into the portion 16 and upon the bottom of the sieve 23. When the container has been filled to the desired extent, the cork 29 is placed in position with the follower plate 32 pressing against the tobacco, there-

by compressing the spring 30 and pressing the tobacco into a mass in the direction of the sieve 23. Then the pipe is turned upright and the mouth applied to the mouth-piece 9 and a lighted match applied to the top of the sieve 23, and suction will cause the air to pass downwardly through the sieve 23 and through the burning tobacco against the sieve and outwardly through the 10 perforations 18 and 19 to the chamber 3 and from the chamber 3 through the passages 8 and 10 to the mouth.

So far as the operation is concerned, the 15 important features to which I wish to call especial attention are the facts that the tobacco is fed upwardly to the sieve 23 as fast as the tobacco is consumed and that the ashes will pass upwardly through the sieve and may be discharged by tilting the pipe 20 sidewise from time to time as desired.

The portion 16 of the container is tapered so that it will be easy for the spring 30 and follower plate 32 to raise the tobacco against the sieve 23. Obviously in this operation 25 if the container were straight or tapered in the other direction there would be a liability of the tobacco choking and resisting the action of the spring.

The sizes and dimensions given are for 30 purposes of illustration and may be varied greatly without departing from the spirit of my invention.

Various changes may be made in the details of construction without departing from 35 the spirit of my invention as claimed.

I claim:

1. A tobacco pipe comprising a bowl having a chamber extending downwardly from its top and a bore extending from the bottom of the chamber through the bottom of the bowl, a bushing in the chamber at the

top of the bowl, a container inserted downwardly through the bushing and through the bottom of the bowl; there being a series of perforations in the container above the 45 bushing and there being a second series of perforations below the bushing; a sieve in the upper end of the container between the two series of perforations, thus producing an ash chamber above the sieve, a plug 50 removably inserted upwardly into the bottom of the container, an expansive coil spring anchored in the plug and extending upwardly into the container, a follower upon the upper end of the spring, and a 55 stem leading from the chamber.

2. In a tobacco pipe, a bowl, a container mounted therein, there being a chamber between the container and the bowl and perforations through the container communicating with the chamber, a sieve fixed in the container above the perforations and below the upper end of the container, thus forming an ash chamber above the sieve, a spring mounted in the lower end of the container 60 and a stem leading from the chamber.

3. In a tobacco pipe, a bowl, a container mounted in the bowl; there being a chamber around the container in the bowl and perforations through the container; a sieve 70 fixed in the container above the perforations and below the upper end of the container thus producing an ash chamber above the sieve, a plug removably mounted in the lower end of the container, a spring removably mounted in the lower end of the container above the plug, and a stem leading from the chamber.

In testimony whereof I have signed my name to this specification.

ALBERT ANGERMAYER.
